Attorney

UNITED STATES PATENT OFFICE.

THOMAS E. COX, OF BIRMINGHAM, ALABAMA, ASSIGNOR OF ONE-THIRD TO JAMES G. TIDWELL AND ONE-THIRD TO WILLIAM P. BLAIR, BOTH OF BIRMINGHAM, ALABAMA.

WRENCH ATTACHMENT.

Application filed July 27, 1921. Serial No. 437,832.

To all whom it may concern:

Be it known that I, THOMAS E. Cox, a citizen of the United States of America, residing at Birmingham, in the county of Jefferson and State of Alabama, have invented 5 certain new and useful Improvements in Wrench Attachments, of which the following is a specification.

My invention relates to an attachment for 10 socket wrenches adapted to enable an operator with the same tool to hold the nut or bolt head on one side of the work and to turn the bolt head or nut on the other side of the work to thereby quickly apply or remove nuts and 15 bolts.

In the present practice it is necessary to 20 apply a wrench or similar device to the bolt head or nut on one side of the work and to hold it while turning by another wrench the nut or bolt on the opposite side of the work, and as a general rule for speedy work it requires one operator for each wrench.

The purpose of my invention is to equip 25 a wrench with an attachment adapted to engage the nut or bolt on the opposite side of the work from the wrench that is being operated and to hold it during the screwing and unscrewing operation.

It is a feature of my invention that this 30 attachment shall be adapted for ready attachment to and detachment from any standard type of wrench having an end socket. The attachment can obviously be modified to suit different classes of work.

My invention in its preferred embodiment 35 only will be best understood by reference to the accompanying drawings, in which:—

Fig. 1 is a plan view of the wrench with 40 my attachment showing the same about to be applied to the work.

Fig. 2 is a side elevation of Fig. 1, the 45 dotted lines showing the manner of attachment of the wrench to the nut grip.

Fig. 3 is a detail perspective view of the 50 nut grip with which the wrench is adapted to detachably connect.

Similar reference numerals refer to like 55 parts throughout the drawings.

I have illustrated my invention in combination with a wrench comprising a brace 60 handle or shank 1 and an end wrench socket 2. The wrench shank adjacent to the socket is cylindrical and adapted, when disposed crosswise, to be inserted between the re-

versely disposed hooks 3 and 4 forming part 55 of the bent metal frame 5. These hooks 3 and 4 are spaced sufficiently, as shown in Fig. 2, to permit the wrench shank to drop between them and there is enough clearance between the overhanging lips of the hooks 60 and the frame to permit the shank of the wrench to be swung into alignment with the body and to be engaged by both hooks which leave it free for rotation and longitudinal play in the frame. In the bight of the bent 65 metal frame 5 I insert and secure by the rivet 6 the shank 7 of the nut grip attachment. This attachment comprises a nut receiving socket 8 connected to the right angled bend at the end of the shank and disposed in alignment with the shank of the wrench 1 when in operating position. An ejector plunger 9 is mounted in the socket 8 free for a longitudinal play limited by its head in the socket and its enlarged outer 75 end, the enlargement at both ends of the ejector preventing its disengagement from the socket 8.

As illustrated in Fig. 1, I show a screw bolt 10 having a castellated nut 11 mounted 80 on its end and disposed on the opposite side of the work 12 from the head of the bolt. In the position of the parts shown in this Fig. 1 the wrench is supposed to be working in vertical position and the nut grip will 85 therefore be free to drop by gravity so that its socket 8 will receive and hold the nut 11. In doing this the frame 5 is free to slip down the shank 1 of the wrench. On thrusting the wrench upwardly to cause its socket 2 to 90 engage the bolt head, the wrench shank will slide through the frame 5 but will remain interlocked therewith so that as the wrench is turned to screw or unscrew the bolt the nut grip attachment 7 is held from turning 95 by the connection of its shank through frame 5 with the wrench and thus the wrench with its attachment is adapted to control both the nut and the bolt notwithstanding that both are on opposite sides of the work.

It is to be understood that the shank 7 of the nut grip will be of such shape as to straddle the edge of the work and permit the nut grip to assume operating position and it therefore follows that the depth of 105 the bow in its shank, as shown in the drawings, is merely illustrative of any bend therein which will enable the nut grip to be ap-

plied to the work. The wrench can be readily detached from its grip attachment by swinging it to the dotted position shown in Fig. 2, and lifting it out from between the jaws 3 and 4.

This invention is not intended to be restricted in scope to the specific embodiments shown, but contemplates such modifications as come within the spirit and scope of the 10 claims.

Having thus described my invention, what I claim as new and desire to secure by Letters Patent, is:—

1. The combination with a socket wrench having a shank portion in alignment with the axis of the wrench socket, of a nut grip socket closed at its outer end and having its inner open end disposed in spaced opposition to the wrench socket, means to slidably 15 connect the grip to the wrench shank, leaving the latter free to rotate about its axis, and an ejector plunger mounted in the grip socket and having a shank projecting through its closed outer end.
2. An attachment for a socket wrench having a wrench shank, comprising a frame 20

having a pair of oppositely disposed overhanging closely associated jaws spaced for the reception between them of a transversely disposed wrench shank, the overhung ends 30 of the jaws being spaced from the frame sufficiently to permit the wrench shank to be slidably engaged under both jaws when swung into alignment therewith, and a nut grip mounted on the frame and having a 35 socket turned towards and aligning with the jaws.

3. The combination with a socket wrench having a cylindrical shank aligning with its socket, of an attachment having a holder 40 socket closed at one end and adapted to align with and face with its open end towards the wrench socket, and a pair of rigidly connected reversely disposed angled elements 45 adapted to slidably connect said attachment socket to the wrench shank, leaving the latter free to turn and move axially relatively to such element.

In testimony whereof I affix my signature.
THOMAS E. COX.
